UNITED STATES PATENT OFFICE

HERMON G. WEINLAND AND GEORGE E. VANCE, OF SPRINGFIELD, OHIO, ASSIGNORS TO THE SAFETY GRINDING WHEEL & MACHINE COMPANY, OF SPRINGFIELD, OHIO, A CORPORATION OF OHIO

MACHINE FOR TRIMMING ABRASIVE WHEELS

Application filed May 22, 1929. Serial No. 365,183.

This invention relates to improvements in machines for truing the faces or peripheries of abrasive grinding wheels.

One of the objects of the invention is to provide for quickly and readily adjusting the position of the cutting tool to allow the tool to first cut in one direction across the working face or periphery of the grinding wheel and then in the other direction, the cuts being from the edges inwardly to obviate danger of chipping the corners or edges of the wheels; a further and more specific object in this connection being to provide means whereby the tool holder may be readily adjusted to two predetermined positions on a feed slide whose direction of movement is fixed so that the tool may be readily positioned at the proper angle with relation to either side of the work without the necessity of adjusting the slide so far as securing the desired angle is concerned.

Another object is to provide power-operated mechanism and controlling means therefor for the various movements of the cutting tool in order to eliminate manual labor and also obviate costly maintenance of screw feeds due to the necessity of eliminating lubrication in machines of this kind.

Another object is the provision of automatic means for varying the speed at which the grinding wheel is rotated to maintain a constant peripheral speed for different sizes of wheels mounted on the machine for trimming or truing purposes.

A further object is to provide for the secure clamping of the tool holding devices, together with controlling means for the actuation of the clamping devices.

Other objects and advantages will appear from the following specifications and claims.

In the accompanying drawings:

Fig. 1 is a top plan view.

Fig. 2 is an enlarged partial front elevation of the tool movement controlling mechanisms,

Fig. 3 is an enlarged sectional view on the line 3—3 of Fig. 2.

Fig. 4 is a side elevation of the machine.

Fig. 5 is also a side elevation, viewed from the opposite as compared to Fig. 4.

Fig. 6 is a partial front elevation.

Fig. 7 is an enlarged fragmentary plan view of a portion of the adjusting means.

Fig. 8 is an enlarged plan view, similar to Fig. 7, with the parts in a different relation.

Fig. 9 is an enlarged sectional view of the tool holding devices.

The machine shown in the drawings and described in the specifications is particularly applicable to the operation of truing the working face or periphery of an abrasive grinding wheel, where it is essential that the face be concentric with the bore and square with the sides of the wheel, and that the wheel have square, un-nicked corners or edges to maintain the wheel in proper balance.

Referring to the drawings, the grinding wheel 1, whose face is to be trued, is mounted in the usual manner on a spindle 2 and secured thereon with the nut 3. The spindle 2 is carried in bearings (not shown) in a bearing support or supports 4 having caps 5 mounted on a main frame casting 6, supported on legs 7, and is rotated by any suitable manner in the direction of the arrow on the wheel 1 (see Fig. 4) there being in this case a pulley 8 keyed to the spindle 2 in the space between the bearing supports 4.

The preferable tool employed in all such truing operations is a cone-shaped hardened steel member 9, formed by stamping flat sheet metal into the cone shape as shown and rigidly secured in one end of a hollow spindle 10; there being a bolt 11 having a conical shaped head 12 passed through the central opening 14 of the tool 9 and through the bore 15 of the hollow spindle 10 and having a nut 13 by means of which the tool is drawn

tightly into the cupped end 16 of the spindle 10 (Fig. 9). The action of the tool or cutter 9 when pressed against a revolving grinding wheel is to break or cut away all portions 5 of the wheel touched by the tool and to turn freely about its own axis at the speed of the grinding wheel by frictional engagement with the wheel, therefore the spindle 10 is journaled in suitable bearings, in the present 10 case, anti-friction ball bearings 17 and 18, the outer races being carried in a shell 19.

A tool-holder block comprising a base member 20 and a cap 21 are bored to receive the shell 19, and when the shell is placed in 15 the bore it is held rigidly by means of the screws 22. The wear on the tool 9 is least, and the cutting action is better performed when the tool is at an angle with the face of the wheel, as shown in Fig. 1, and since the 20 cuts are taken from each edge inwardly toward the center of the wheel face, it follows that there are two preferred positions for the tool and its holder, shown in full and dotted lines in Fig. 1, which position must be accurately the same either side of the center 25 of the arc of movement. Accordingly, to locate the tool-holder in either of the two positions there is a plunger 23 slidably mounted in a recess 24 in the boss 25, preferably an 30 integral part of the block 20 and connected therewith by arms 26, a spring 27 being interposed between the head 23' of the plunger and the top of the recess. A hand lever 28 having a forked end is pivoted on a pin 35 29 journaled in a block 30, attached to the cap 21, by means of which the plunger may be lifted against the tension of the spring 27.

The tool-holder is mounted at one end of 40 a slide 31, with the center lines of the tool 9 and the wheel spindle 2 coinciding, and for the purpose of obtaining an equal angle in either of the positions of the tool, there are two bushings 32 set in the slide 31 which receive the head of the plunger 23 to position 45 the tool; the bushings being set an equal distance on each side of the center line at right angles to the face of the wheel 1. To provide a central point about which the tool-holder may be turned when shifting to either of the 50 two positions, there is, on the under side of the base 20, a boss 33, fitted in a recess 34 in the slide 31.

The slide 31 is supported on a saddle 35 and has a reciprocating movement on the 55 saddle parallel to the longitudinal axis of the spindle 2. As has been mentioned previously, the use of lubricants tends to present oily surfaces that catch and hold the abrasive dust. It is therefore desirable to operate the 60 machine with the minimum of lubrication, involving excessive manual labor, and to obviate this, hydraulic power is employed. On the slide 31 is mounted a cylinder 36 secured thereto by clamps 36', having the usual piston 65 (not shown) and piston rod 37, the outer

end of which is secured to a standard 38, which in turn is secured to the saddle 35, although it will be evident that similar results would be obtained if the cylinder were secured to the saddle 35, and the piston to the 70 slide. It will now be seen that if pressure is applied to the right hand side of the piston, in the present case, the slide will move to the right, and vice-versa.

In order to quickly and securely clamp the 75 tool-holder to the slide 31, there are provided means for accomplishing this by hydraulic power, comprising a cylinder 39 attached to the slide, a beam 40 pivoted on a pin 42 in a pair of standards 41. The end 43 of the beam is pivoted to a pin 44 carried by the jaws of a clevis 45 threaded on the upper end of the piston rod 46 of the cylinder 39. When pressure is applied to the lower side of the piston in the cylinder 39, there will be an upward movement of the end 43 of the beam 40, and a corresponding downward movement of the opposite end 47, and thus pressure may be applied to the tool-holder to rigidly hold it, through the medium of a block 48 resting on the cap 21. When it is desired to shift the 85 tool to another position, the pressure is applied to the upper end of the cylinder, which will lift the beam end 47, and by means of the lever 28 the plunger 23 may be withdrawn 90 from the locating bushing 32, after which the entire tool-holder may be shifted to the opposite position, after being withdrawn from the wheel in the manner to be later explained. 95

The saddle 35 is carried on ways 49 which are integral parts of the main frame structure 6, the movement of the saddle being also reciprocatory but in the direction to and from the spindle at right-angles thereto. As is the case with the slide 31, the saddle 35 is also reciprocated by hydraulic power, there being a cylinder 50, one end of which is secured to the frame 6, and having a piston 51, a rod 52 and other associated common parts similar to the other cylinders. The rod 52 extends forwardly towards the front of the machine and is secured to the saddle 35 by means of a block 53, there being a nut 54 at each end of the block 53 on the threaded end of the rod 52. It will be evident from this that there will be a forward and rearward motion imparted to the saddle 35, and likewise to the tool 9, when pressure is alternately applied to either end of the cylinder 50, by means of which the tool approaches or is withdrawn from the wheel being trued. 115

The limit of travel of the saddle 35 is fixed by stops 55 and 55' secured to the frame 6. However it is evident that the diameter of the wheel being faced is determined by the 120 position of the tool 9, and in order to adjustably limit the movement of the saddle 35 toward the wheel 1, there is provided a screw 56 threaded in the block 53, and journaled in a boss 57 at the front end of the frame 6. 125

On the outer end of the screw 56 is fixed a hand-wheel 58 having a hub 59 which contacts with the boss 57, on forward movement of the saddle 35 toward the spindle 2. Therefore it will be seen that when pressure is applied to the end 50' of the cylinder 50, the movement of the saddle 35, and consequently of the tool 9, is to the front of the machine, or toward the stops 55, while when the pressure is reversed, the saddle will advance toward the stops 55', or until contact is made between the hub 59 and boss 57.

It is customary to pass the tool 9 from edge to center of the abrasive wheel a number of times, according to the amount of material that must be taken off to reduce the wheel to the desired diameter, and as a truer surface is obtained by a comparatively light final cut, provision is made for rapidly obtaining a uniform adjustment for this light cut, there being interposed between the hub 59 and boss 57 one or more shims, only one of which, 60, is shown in the present case, the function of which is, when interposed, to stop the travel of the saddle 35, and when removed, to permit a further advancement of the saddle equal to its thickness. For convenience in operation, the shim 60 is hinged on a pin 61 to the frame 6 in alignment with the boss 57, and has an open slot 62 by means of which it may embrace the screw 56.

The control of the various movements of the slide 31 and saddle 35, and also the clamping arrangement for the tool-holder, is accomplished by means of a plurality of valves, 63, slidably fitted in a valve block 64, and actuated by levers 65. Fluid, preferably oil, under pressure, is conducted through a pipe 66 and through a series of drilled openings in the valve block 64 to each end of each valve, another series of openings 67 leading to connections 68 convey the fluid to the respective ends of the cylinders. Each valve may be at rest in either of the positions supplying pressure to a cylinder, at which time the series exhaust ports 69, which are always in registry with the centers of the valves, will exhaust the opposite end of a cylinder under pressure. The exhaust ports 69 connect with an opening 70 from a pipe 71 conducts the fluid to the pressure pump.

To facilitate stopping the spindle 2 when a wheel is to be removed, a brake-drum 72 is secured to the spindle 2 with which cooperates a brake band 72' connected in the usual way to a foot-pedal 73. Inasmuch as the preferred peripheral speed is desired for all wheels regardless of diameter, provision is made for varying the speed at which the spindle is rotated to accord with the size of the wheel. If the machine is driven by a variable speed electric motor, any of the methods by which the speed is altered, such as the introduction of resistances in the shunt field circuit in such manner as to allow a

change in speed in inverse ratio to the diameter of the wheel, may be employed. In the present instance, there is provided a rheostat 74 on the shaft of which is a sprocket 75 over which a chain 76 is passed to another sprocket 77 on the main frame. The lower reach of the chain is connected to a downwardly extending arm 78 secured to the saddle 35, and as the saddle moves along its ways, there is a corresponding movement in the lower reach of the chain, thus turning the rheostat with the effect that there will be an increase or decrease in the speed of rotation of the spindle 2 in proportion to the size of the wheel.

In operation, the wheel to be trued is placed on the spindle 2, and the tool is shifted to either of its angular positions, after which it is clamped in place by admitting pressure to the lower end of the cylinder 39. By manipulating the proper valves, the tool, by movements of the slide and saddle, is brought near the edge of the wheel, and if there is not, in the judgment of the operator, too great an amount of material to be removed, the shim is interposed by swinging it to place before the boss 57, the screw 56 being turned inwardly until the hub 59 contacts the shim, after which the proper valve is manipulated to exert the full pressure of the cylinder 50 on the screw 56, holding the saddle firmly in this position. The cutting operation is then performed by moving the tool-carrying slide toward the center of the wheel, and after the desired degree of cut has been made, further movement of the slide is arrested by placing the proper valve in the neutral position. The valve controlling the saddle movement is then reversed to move the tool from the wheel a sufficient distance, when the slide is again moved in the original direction, the tool however not clearing the wheel during this movement.

When the slide has progressed well beyond the uncut edge of the wheel, the pressure on the tool-holder is relieved, the tool is shifted to the opposite angular position and again clamped. The slide is then moved to carry the tool against the wheel, continuing until the remainder of the rough periphery receives the initial cut. If the wheel is now near the desired size, the saddle is moved to relieve the pressure on the shim, after which it is lifted away, and the saddle again moved to the stop afforded by the contact of hub and boss when a cut equal to the thickness of the shim is taken similar to the manner described.

Having thus described our invention, we claim:

1. In a machine of the character described, a rotatable spindle to support and rotate an abrasive wheel, a supporting member, a tool and its holder mounted on said member, means for moving said member toward said wheel to adjust the cutting position of said tool with relation to said wheel, electric mo-

tor speed controlling devices, and a connection between said movable support and said devices.

2. In a machine of the character described, a rotatable spindle to support and rotate and rotate an abrasive wheel, a movable supporting member, a tool and its holder mounted on said supporting member, means for moving said member toward said wheel to adjust the tool with relation to said wheel, a controlling rheostat, a connection between said rheostat and said movable supporting member.

3. In a machine of the character described, a rotatable spindle to support and rotate an abrasive wheel, a movable supporting member, a tool and its holder mounted on said supporting member, means for moving said member toward said wheel to adjust the tool with relation to said wheel, a controlling rheostat, a connection between said rheostat and said movable supporting member, said connection consisting of a sprocket on the shaft of the rheostat, a second sprocket on the frame of the machine, a chain passing over said sprocket, and a connection between said chain and said movable supporting member.

4. In an apparatus of the character described, a rotatable spindle adapted to support and rotate an abrasive wheel, a tool support movable in a fixed direction with respect to said spindle, a tool holder and tool adjustably mounted on said support to permit the tool to be positioned in opposite uniform angular relation with the sides of said wheel, and means for clamping the holder to said support in either position of adjustment, said means including a fluid pressure cylinder and piston rod carried by said support, a clamp and a connection between said piston rod and clamp.

5. In an apparatus of the character described, a rotatable spindle adapted to support and rotate an abrasive wheel, a movable support, a tool holder and tool swivelly mounted on said support whereby the tool may be positioned in opposite uniform angular relation with the sides of said wheel, means for accurately positioning the tool in either direction, and means for clamping the holder to said support including a fluid pressure cylinder and its piston and a pivoted clamping lever all carried by said support, one end of said lever having a connection with the piston of said cylinder and the other end of said lever adapted to exert pressure on said holder.

6. In an apparatus of the character described, a rotatable spindle adapted to support and rotate an abrasive wheel, a tool support movable in a fixed direction with respect to said spindle, a tool holder and tool adjustably mounted on said support to permit the tool to be positioned in opposite uniform angular relation with the sides of said wheel,

means for clamping the holder to said support in either position of adjustment, said means including a fluid pressure cylinder and piston rod carried by said support, and a pivoted clamping lever, one end of which is adapted to bear upon the holder and the other end of which is pivotally connected to said piston rod.

In testimony whereof, we have hereunto set our hands this 15th day of May 1929.

HERMON G. WEINLAND.
GEORGE E. VANCE.
